CORE BARREL

Guy C. Oliver, Glendale, Calif.

Application May 10, 1937, Serial No. 141,601

9 Claims. (Cl. 255—72)

This invention relates to core barrels.

The general object of the invention is to provide a core barrel including an inner and an outer member wherein novel means is provided for supporting the members.

A further object of the invention is to provide a core barrel including an inner and an outer member with means to provide circulation between the members and wherein the inner member is provided with a novel end closure which aids in producing circulation between the barrels.

Another object of the invention is to provide a novel means for rotatably supporting the upper end of a core barrel.

An additional object of the invention is to provide a novel means for rotatably supporting the lower end of a core barrel.

Other objects and the advantages of my invention will be apparent from the following description taken in connection with the accompanying drawings, wherein:

Fig. 1 is a central sectional view through a core barrel showing my invention;

Fig. 2 is a fragmentary view similar to Fig. 1 on an enlarged scale;

Fig. 3 is a section taken on line 3—3 Fig. 1;

Fig. 4 is a view similar to Fig. 1 showing a modification of my invention;

Fig. 5 is a fragmentary, enlarged, sectional view showing the modification;

Fig. 6 is a section taken on line 6—6 Fig. 5;

Fig. 7 is a view similar to Fig. 1 showing a further modification; and

Fig. 8 is an enlarged, fragmentary section showing the further modification.

Referring to the drawings by reference characters I have shown my invention as embodied in a core barrel which is indicated generally at 10. As shown the core barrel includes a shell 11 which is connected to a coupling 12 which in turn is connected to a sub 13. The sub 13 is connected to the lower end of a drill string 14.

The lower end of the shell is connected to a collar 14 which has a bit 15 secured to the lower end thereof. The bit 15 includes cutting teeth 16 and reamer blades 17. The reamer blades are preferably disposed at right angles to each other and preferably at different distances from the lower end of the bit.

The bit 15 is provided with downwardly directed circulation apertures 18 and lateral apertures 19. The apertures 19 communicate at their inner end with the bore 20 of the bit and at their outer ends intersect the aperture 18. The apertures 18 at their upper end communicate with a

peripheral channel 21 in the inner wall of the bit 15. The upper end of the bit has threads 22 thereon which engage similar threads on the collar 14.

The coupling 12 is provided with an inwardly directed flange 23 which includes apertures 24. The flange includes a hub 25 which is internally threaded and which receives a stem 26 which has a lock cap 27 secured thereto. The stem is provided with a wrench engaging portion 28 at its upper end by means of which the stem may be rotated. As shown in the drawings the lock cap 28 is disposed just below a shoulder 29 in the sub 13.

The stem 26 includes a cylindrical portion 30 and a reduced cylindrical portion 31 which terminates in a threaded portion 32. Mounted upon the cylindrical portion 30 I show a plug 37 which is hollow to receive the cylindrical portion and which includes a packing gland 38.

Mounted on the reduced portion 31 I show antifriction bearings 39 which preferably comprise radial and thrust bearings. The upper bearing element engages the plug 37 while the lower bearing element engages a threaded nut 40 on the end 32. A lock washer 41 serves to hold the nut 40 in place.

The outer surface of the plug 37 is threaded to receive the threaded end of a support member 42 the lower end of which is threaded as at 43 to receive an outer core barrel 44. This outer core barrel includes a lower portion 45 which slidably fits within the bit bore 20 and includes a peripheral shoulder 46 which limits the down movement of the outer barrel.

The support member 42 includes a depending flange 47 which includes a circulation diverging member 48 and apertures 49 about the member 48. The flange 47 supports an inner core barrel 50 which is spaced a slight distance from the outer core barrel to provide an annular circulation passage 51. The inner core barrel extends as at 52 beyond the outer core barrel and receives within its lower end a core catcher assembly 53 which includes an upper member 54 and a lower member 55.

The upper member 54 includes a bevelled upper surface 56 and a rabbet 57 which receives a flange 58 on the lower member 55. The member 54 as shown includes a dove tail peripheral groove 59 in which a rubber lining 60 is vulcanized. The lining 60 includes a dove tail portion 61 which fits the groove 59. The lower member 55 includes a plurality of slots 63 in which catches 64 are pivoted. Springs 65 normally

urge these catches forward. The interior of the core catcher assembly is provided with a plurality of resilient fingers 66 which are secured to the lower member 55 as by rivets 67.

5 The members 54 and 55 constitute a slip member which can be readily removed from the inner core barrel 50.

The interior diameter of the core catcher assembly is practically the same as that of the core cut by the bit while the interior diameter is slightly greater than that of the core. Consequently very little friction occurs between the core and the core barrel and what friction does occur is confined to the portion adjacent the core 10 catcher slip member 60.

In use the core barrel is secured to the end of the drill string and normal circulation passes down the drill string and through the space 20 between the outer core barrel and the interior 20 of the shell 11 and passes out through the apertures 18 into the hole. Some of the circulation fluid passes with the core into the inner barrel 50 whence it impinges against the circulation diverging member 48 and thence passes outwardly 25 through the apertures 49 into the space 51 between the inner and outer barrel, thence downwardly and out through the apertures 19. The fluid passing through the aperture 18 produces in effect an injector action thus assisting to 30 draw the fluid from the aperture 19.

The circulation through the core barrel is aided by the diverging member 48 which tends to direct fluid to all of the holes 49 thus tending to prevent accumulation of fluid in the end of the 35 barrel.

After the core has been taken the core barrel is withdrawn and removed from the drill string. The shell 11 is then separated from the coupling allowing access to the core barrel. Adjustment 40 may be effected by removing the cap 29 and rotating the post 26 thus shifting the core barrel relative to the bit.

In Figs. 4, 5 and 6 I have shown a modification of my invention. As here shown the core barrel indicated generally at 80 includes a shell 81 which 45 is connected at one end to a sub 82. The sub 82 is connected to the lower end of a drill string 83.

The lower end of the shell 80 is connected to a collar 84 which has a bit 85 secured to the 50 lower end thereof. The bit 85 includes cutting teeth 86 and reamer blades 87. The reamer blades are preferably disposed at right angles to each other and preferably at different distances from the lower end of the bit.

55 The bit 85 like the bit 15 is provided with downwardly directed circulation apertures 88 and lateral apertures 89. The apertures 89 communicate at their inner end with the bore 90 of the bit and at their ends intersect the apertures 88.

60 The apertures 88 at their upper end communicate with a peripheral channel 91 in the inner wall of the bit 85. The upper end of the bit has threads 92 thereon which engage similar threads on the collar 84.

65 The bit bore 90 includes a lower reduced bore 93 thus providing a shoulder portion 94 on which an antifriction member, such as a ball race 95, is mounted. This ball race is held in place by a locking ring collar 96 which engages threaded 70 portions on the lower end of the bore 90. The lower element of the ball race is engaged by a flange 98 on a collar 99 which is threaded to an inwardly directed flange 100 on a ring 101. The flange 100 engages the top of the bearing 95.

75 The upper portion 102 of the ring engages an

outer element 103 of a core barrel being threaded to the lower end of this outer element. A lock ring 104 serves to hold the parts in adjusted position. The outer barrel 103 is provided with guide ribs 105 at its upper end and is threaded internally to receive a closure 106. The closure or coupling 106 includes a reduced portion 107 which includes a skirt 108 having apertures 109 therein to allow circulation passage. To the lower end of the skirt 108 I secure an inner core barrel element 112. The closure 106 includes a circulation directing projection 113 which extends below the apertures 109 by means of which circulation is provided between the outer barrel 103 and the inner barrel 112, the two barrels being spaced 15 apart as shown.

The inner barrel 112 is provided with a core catcher assembly 117 which includes an upper member 118 and a lower member 119. The member 118 as shown includes a dove tail peripheral 20 groove 120 in which a rubber lining 121 is vulcanized. The lining 121 includes a dove tail portion 122 which fits the groove 120. The lower member 119 is shown as including a plurality of slots 123 in which catches 124 are pivoted. Springs 125 normally urge these catches forward. The interior of the core catcher assembly is provided with a plurality of resilient fingers 126 which are secured to the lower member 119 as by rivets 127. The members 118 and 119 constitute 30 a slip member which can be readily removed from the inner core barrel 112.

As explained the interior diameter of the core catcher assembly is practically the same as that of the core cut by the bit while the interior diameter of the inner barrel is slightly greater than that of the core so that but little friction occurs between the core and the core barrel and what friction does occur is confined to the portion 35 adjacent the core catcher slip member 117.

In use the modified core barrel is secured to the end of the drill string and circulation occurs as previously described. Some of the circulation fluid passes into the inner barrel 112 whence it 40 impinges against the circulation diverging member 113 and thence passes outwardly through the apertures 109 into the space 51' between the inner and outer barrel, thence downwardly and out through the apertures 89. The fluid passing the aperture 89 produces in effect an injector 50 action thus assisting to draw the fluid from the aperture 89.

In this construction just described it will be observed that the entire support of the core barrel is on the bearings 95 and that both the inner 55 and outer core barrel may remain stationary while the bit turns. Adjustment of the inner core barrel towards and from the digging end of the bit is effected by loosening the lock nut 104 then turning the outer core barrel after which 60 the lock nut 104 is tightened.

In Figs. 7 and 8 I show a further modification of my invention wherein the bit 130 is provided with a collar 131 which engages a sleeve 131' which engages a sub 132. The bit is provided 65 with circulation grooves 133 and 134 and its general construction is similar to that previously described.

The core barrel in this further modification includes an outer barrel 135 and an inner barrel 70 136. The outer barrel 135 includes a threaded lower portion 137 which engages similarly threaded portion in the bore 138 of the bit. The outer barrel 135 is provided with a closure 139 in which a threaded post 140 is mounted. This post 75

includes a wrench engaging portion 141 and a lock cap 142. The post 140 is provided with a flange 143 which engages a ball race 144 which in turn engages a closure 145 mounted on a coupling member 146.

The closure 145 is provided with a recess 147 in which an unthreaded portion 148 of the post 141 extends. The coupling member 146 is threaded at its lower end to match threaded portions 148 on an inner core barrel 136. This inner core barrel is threaded to a collar 149 which is engaged by a lock collar 150. The collar 149 slides in the bore 138 and at its lower end rests on a ball race 151 which is disposed in a recess 152 in the bit. The core catcher assembly 153 is shown as identical with that previously described and comprises a lower member 154 and an upper member 155 mounted within the lower end of the inner core barrel 136.

In this further modification of my invention it will be noted that the outer core barrel is mounted on the bit and rotates with the bit while the inner core barrel is supported on the bearings 151 and remains stationary. The upper end of the inner core barrel is held against upward movement by means of engaging with the ball race 144. Adjustment of the inner core barrel is effected by loosening the clamping collar 150 and the clamping cap 142 and then rotating the inner core barrel relative to the collar 144 and by rotating the stem 140 relative to the closure 139 after which the locking collar 150 and the lock cap 142 are secured in position.

The operation of the further modification is the same as that previously described and repetition of a description of this operation is believed unnecessary.

Having thus described my invention I claim:

1. In a core barrel, a stem, means to support the stem, a core barrel support rotatably secured to said stem, said core barrel support including a skirt, an outer core barrel on said core barrel support, an inner core barrel on said skirt and spaced from the outer barrel, said skirt having apertures affording communication between the interior and the exterior of the inner barrel and a core catcher on said inner barrel.

2. In a core barrel, a bit assembly having a central bore therethrough, a stem, means to support the stem on the bit assembly, a core barrel support rotatably secured to said stem, said core barrel support including a skirt, an outer core barrel on said core barrel support, an inner core barrel on said skirt and spaced from the outer barrel, said skirt having a plurality of radial apertures affording communication between the interior and the exterior of the inner barrel, said outer core barrel being slidable in said core, a core catcher on said inner barrel, said core catcher assembly including an upper and a lower member, said lower member having a plurality of core engaging members.

3. In a core barrel, a bit having a bore, a coupling on the bit, a stem mounted on said coupling, a core barrel support on said stem, said core barrel support having a skirt, an outer core barrel on said core barrel support, an inner core barrel on said skirt and spaced from the outer barrel having a plurality of apertures affording communication between the interior and the exterior of the inner barrel, said outer core barrel being slidable in said bore and a core catcher assembly on said inner barrel.

4. In a core barrel, a bit having a central bore, a coupling, means to secure the coupling to the

bit, a hubbed spider in said coupling, a stem mounted on said spider, a core barrel support on said stem, said core barrel support having a skirt, an outer core barrel on said core barrel support, an inner core barrel on said skirt and spaced from the outer barrel and having a plurality of apertures according communication between the interior and the exterior of the inner barrel, said outer core barrel being slidable in said bore, a core catcher assembly on said inner barrel, said core catcher assembly including a plurality of spring pressed catches therein.

5. In a core barrel, a bit having a central bore, a coupling secured to said bit, a spider in said coupling, a hub on said spider, a stem engaging said hub, said stem having a cylindrical portion thereon, an apertured plug on said cylindrical portion, a core barrel support secured to said plug, said core barrel support having a skirt, an outer core barrel on said core barrel support, an inner core barrel on said skirt and spaced from the outer core barrel, means to afford communication between the interior and the exterior of the inner barrel, said outer core barrel being slidable in said bore and a core catcher assembly on said inner barrel, said core catcher assembly including an upper and a lower member, said lower member having a plurality of spring pressed catches therein.

6. In a core barrel, a bit having a central bore, a collar on which said bit is supported, a shell secured to said collar, a coupling on said shell, a sub on said coupling, a spider in said coupling, a hub on said spider, a stem engaging said hub, a plug on said stem, a bearing on said stem and engaging the plug, a core barrel support threadedly secured to said plug, said core barrel support having a skirt, an outer core barrel on said core barrel and spaced from the shell, an inner core barrel on said skirt and spaced from the outer core barrel, means to afford communication between the interior and the exterior of the inner barrel, said outer core barrel being slidable in said bore and a core catcher assembly on said inner barrel.

7. In a core barrel, a bit having a central bore, a collar on which said bit is supported, a shell secured to said collar, a coupling on said shell, a sub on said coupling, a spider in said coupling, a hub on said spider, a stem engaging said hub, said stem having a cylindrical portion thereon, an apertured plug on said cylindrical portion, said stem including a reduced portion, a bearing on said reduced portion, a core barrel support threadedly secured to said plug, said core barrel support having a skirt, said core barrel support including a transverse partition forming a chamber for said bearing, an outer core barrel on said core barrel support and spaced from said shell, an inner core barrel on said skirt, means to afford communication between the interior and the exterior of the inner barrel, said outer core barrel being slidable in said bore, a core catcher assembly on said inner barrel, said core catcher assembly including an upper and a lower member, said lower member having a plurality of spring pressed catches therein.

8. In a core barrel, a bit having a central bore, a collar on which said bit is supported, a coupling, means to secure the coupling to the collar, a hubbed spider in said coupling, said hub having a threaded aperture, a stem having threads thereon and fitting said hub aperture, said stem having a cylindrical portion thereon, an apertured plug rotatably mounted on said cylindrical portion, a

core barrel support threadedly secured to said plug, said core barrel support having a skirt, said core barrel support including a transverse partition forming a chamber for said bearing, an outer core barrel on said core barrel support, an inner core barrel on said skirt and spaced from the outer barrel, said core barrel support having a circulation diverging projection, and having a plurality of radial apertures adjacent to the projection affording communication between the interior and the exterior of the inner barrel, said outer core barrel being slidable in said bore, a core catcher assembly on said inner barrel, said core catcher assembly including an upper and a lower member, said lower member having a plurality of spring pressed catches therein.

9. In a core barrel, a bit having a central bore, a collar on which said bit is supported, a shell secured to said collar, a coupling on said shell, a sub on said coupling, a spider in said coupling, a hub on said spider, said hub having a threaded aperture, a stem having threads thereon and fitting said hub aperture, a lock cap engaging said

stem and said hub, said stem having a cylindrical portion thereon, an apertured plug on said cylindrical portion, said plug including a packing gland engaging said cylindrical portion, said stem including a reduced portion, a bearing on said reduced portion, a nut engaging said bearing, a core barrel support threadedly secured to said plug, said core barrel support having a skirt, said core barrel support including a transverse partition forming a chamber for said bearing, an outer core barrel on said core barrel support, an inner core barrel on said skirt, said core barrel support having a circulation diverging projection and having a plurality of radial apertures adjacent to the projection affording communication between the interior and the exterior of the inner barrel, said outer core barrel being slidable in said bore, a core catcher assembly on said inner barrel, said core catcher assembly including an upper and a lower member, said lower member having a plurality of spring pressed catches therein.

GUY C. OLIVER.
